FIG. 1

FIG. 2

FIG. 3

Fig. 1 is a perspective view of a toothbrush showing my new design;

Fig. 2 is a side elevational view thereof;

Fig. 3 is a top plan view thereof.

The design for the toothbrush disclosed is characterized by the staggered disposition of the three rows of bristles and their relative length with respect to each other as shown.

I claim:

The ornamental design for a toothbrush, substantially as shown and described.
